AUTOMATIC MEANS FOR MAINTAINING A PUMP PISTON IMMERSED IN LUBRICATING OIL

Benjamin F. Schmidt, Los Angeles, Calif.

Application January 30, 1956, Serial No. 562,171

20 Claims. (Cl. 103—179)

This invention relates to pumps of the reciprocating piston type such as are employed in oil well operations, and has as its primary object the provision of a pump of this character in which the working surfaces of the piston are maintained immersed in a body of lubricating oil; said oil substantially retained in its original position and volume by a body of mercury above and below said oil, and protected against mixing with abrasives due to the presence of sand or grit contained in liquid being pumped, by the mercury operating as a seal or separator at all points between the liquid being pumped and the sealing contacts of the pump.

A particular object of the invention is to provide a method and an assemblage whereby a body of lubricating oil may be confined in the working zone of a pump piston so as to maintain a substantial body of the lubricating oil between the wearing surfaces of the pump piston and contiguous walls of the pump whether externally of the piston or internally thereof.

Another object is to provide a means whereby a substantial volume of the lubricating oil will be maintained in the pump at the opposite ends of the piston at all times during operation thereof thereby insuring functioning of the piston within a body of the lubricating oil throughout operation of the pump, and also to provide booster means whereby such of the lubricating oil as may leak past the sealing rings and piston will be automatically returned to the side of the piston from whence it came.

Another object is to provide an arrangement whereby the body of lubricating oil will be confined in the pump between bodies of mercury in such manner as to prevent loss of the lubricating oil and thereby maintain its original volume, and in such manner that the mercury will serve as a shield or barrier to prevent access to the body of lubricating oil by liquid being pumped as well as solids contained in such liquid.

A further object is to provide a pump embodying a piston body the working face of which is encompassed by a body of lubricating oil entrapped in the pump by bodies of mercury, wherein the piston body is sealed at all times in the lubricating oil, and its working face maintained out of contact with the mercury, as distinguished from pumps embodying a mercury body in which the piston works.

An important feature of the invention resides in providing a construction in the pump whereby the several parts thereof that are contacted by mercury are coated with a metal, such as silver or tin, with which mercury will react to form an amalgam and thereby provide a wiping contact between the mercury and the coated surfaces so as to prevent fluids being pumped from adhering to the surfaces of said pump parts and thus prevent the liquid being pumped and solids contained therein from being drawn into the mercury and effecting contamination thereof.

With the foregoing objects in view together with such other objects and advantages as may subsequently appear, the invention resides in the parts and in the com-

2

bination, construction and arrangement of parts herein-after described and claimed, and as illustrated by way of example in the accompanying drawings in which:

Fig. 1 is a view in vertical section of a barrel type piston pump depicting the invention as applied with portions broken away and showing the pump free of liquid;

Fig. 2 is a view in vertical section of the barrel portion of the pump shown in Fig. 1, with parts broken away;

Fig. 3 is a view in vertical section partly in elevation of the pump piston shown in Fig. 1, parts being broken away;

Fig. 4 is a view in vertical section of a booster employed in conjunction with the piston shown in Fig. 3 and showing it as detached;

Fig. 5 is a detail in cross section taken on the line 5—5 of Fig. 1;

Fig. 6 is a detail in cross section as seen on the line 6—6 of Fig. 1;

Fig. 7 is a detail in cross section taken on the line 7—7 of Fig. 4;

Fig. 8, 9, and 10 are enlarged views in vertical section respectively of the upper, intermediate and lower portions of the pump shown in Fig. 1, and illustrating the pump as equipped with a body of lubricating oil confined in a body of mercury and encompassing the pump piston;

Fig. 11 is a modification of the construction shown in Fig. 8, the view being in vertical section with parts broken away of a piston pump in which the piston encompasses a stand pipe and has an internal working face presented to the pipe, and showing the manner of constructing the pump to carry out the invention;

Fig. 12 is an enlarged partial section taken on the line 12—12 of Fig. 11 showing the structure equipped with the body of lubricating oil and its confining body of mercury;

Fig. 13 is a detail in cross section taken on the line 13—13 of Fig. 11;

Fig. 14 is a detail in cross section taken on the line 14—14 of Fig. 11;

Fig. 15 is a detail in cross section taken on the line 15—15 of Fig. 11; and

Fig. 16 is a detail in cross section taken on the line 16—16 of Fig. 11.

Referring to the drawings more specifically, reference now being had to Figs. 1 to 10 inclusive, A indicates an upstanding cylindrical pump barrel, B designates generally the pump piston which is designed to be surrounded by and confined in part in a body of lubricating oil in said barrel, and C denotes a booster which is associated with the piston B for returning such oil as leaks past the piston body back to the side from whence it came.

The pump barrel A as particularly shown in Fig. 2 is fitted at its lower end in the usual manner with a conventional intake section a and has its upper end leading to a point of discharge. The section a is formed with an inlet a' from which leads a stand pipe 18 extending axially of and spaced from the barrel A equipped with a foot valve b in an enclosing housing 17 and fitted at its upper end with a ball check valve 19 in a cage 20, as is common in oil-well pump construction.

In carrying out the invention as applied to the barrel type of pump, the barrel A is fitted on its interior at a suitable point in the length thereof with a fixed sleeve 21 which encompasses the stand pipe 18 in spaced concentric relation thereto and is also spaced from the inner periphery of the barrel A, the sleeve 21 being fitted at its upper end with a collar 22 which extends outward to the barrel A and is attached to the latter as by screws 23 which pass through openings 23' in the pump barrel and are threaded into engagement with the collar. At least one of the openings 23' is utilized as a means for introducing lubricating oil into the pump, as will be later de-

scribed. Sealing rings 24 are disposed in the joint between the collar and barrel to render it leak proof. The collar 22 thus closes the upper end of the space 25 extending between the sleeve 21 and the barrel A.

The piston B is constructed as particularly shown in Fig. 3 and embodies a length of tubing 26 which is open at its ends and is arranged over the stand pipe 18 in spaced concentric relation thereto and has its upper portion leading longitudinally through the sleeve 21 in spaced relation thereto.

The upper end of the tubing 26 is screwed into a coupling 27 fitted with an end wall 28 engaged with the lower end of a pump rod 29 and embodying a cage 30 housing a ball check valve 31 normally closing an outlet port 32 in a septum 33 formed in the coupling 27.

The tubing 26 is formed intermediate its ends exteriorly thereof with a piston body 34 fitted with a series of spaced sealing rings 35 bearing on the inner surface of the pump barrel A in the usual manner. The end portions of the tubing 26 constitute reduced diameter piston portions extending above and below the piston body. Rigidly mounted on the tubing 26 above the piston body 34 is a sleeve 36 which is open at its upper end and when assembled overlies the sleeve 21 in spaced telescopic relation thereto, the lower end of the sleeve 36 being closed by a wall 37 spaced a short distance above the upper end of the piston body 34. A series of passages 38 lead longitudinally through the piston body 34 which are normally closed at their upper ends by an annular plate valve 39 which seats on the upper end of the piston body 34 under the urge of an accordion spring 40 bearing between the valve 39 and the wall 37.

The passages 38 open to the lower end of the piston body to a space 41 lying between the barrel A and the lower portion of the tubing 26 as shown in Fig. 9, and which space 41 leads downward to the upper end of the booster C which latter is frictionally supported between the tubing 26 and the barrel A for longitudinal sliding movement relative thereto.

The booster C comprises a cylindrical shell 42 the upper portion of which encompasses the lower end portion of the piston tubing 26 and the lower end portion of which terminates in a narrow inturned flange 43 which underlies the lower end of the tubing 26 and encompasses the stand-pipe 18 in spaced relation thereto.

The upper end of the booster shell 42 terminates in a piston head 44 having frictional engagement with the tubing 26 and the barrel A through the medium of resilient sealing rings 45 on the inner periphery of the piston head 44 and a resilient sealing ring 46 on the outer periphery of the piston head 44. The inner rings 45 are designed to have greater frictional engagement with the tubing 26 than the outer ring 44 with the barrel A thus creating a differential in the frictional engagement between the piston head and the tubing and barrel such that the piston head will tend to move with the tubing 26 yet be sealed relative to the barrel.

The space between the margin of the flange 43 and the stand pipe 18 constitutes a valve controlled passage 47 which is normally partially closed by a ring valve 48 formed on a sleeve 49 slidably encompassing the lower end portion of the shell 42, the sleeve 49 being fitted with pins 50 which project through longitudinal slots 51 in the shell 42 and are engaged by a thrust spring 52 bearing on the flange 43 of the shell so as to seat the ring valve 48 over the passage 47 and partly close the latter. The valve 48 is formed at the juncture with the sleeve 49 with a series of slots 48' constituting valve outlets offset relative to the passage 47 and opens to the latter when the valve 48 is in its open position.

The ring valve 48 is fitted with a plurality of upstanding pins 53 which extend through holes 53' in the flange 43, the upper ends of the pins 53 normally extending a short distance above the flange 43 in alignment with and in the path of travel of the lower end of the piston tubing

26, whereby opening of the valve 48 is effected by the end of the tubing 26 being brought into engagement with the pins 53 and caused to depress the latter in opposition to the spring 52. The lower end of the tubing 26 is formed with open ended slots 54 through which the pins 50 freely extend with their inner ends projecting interiorly of the tubing 26 where they are engaged by the spring 52. The booster shell 42 is formed on the interior thereof with a longitudinal channel 55 slidably engaged by a projecting element 56 on the tubing 26 as shown in Figs. 6 and 10. A plurality of such channels and elements may be provided as occasion may require. The element 56 is here shown as comprising a threaded lug which is screwed into the tubing 26 and is formed with a recess in which is seated a spring 57 arranged to bear against the bottom of the channel 55 in frictional engagement therewith and thereby cooperate with the resilient rings 45 in yieldably and adjustably opposing relative movement of the piston tubing 26 and the booster shell 42. As a means for enabling assemblage of the element 56 in the channel 55, the shell 42 is formed adjacent the lower end thereof with apertures 58 arranged opposite the channel 55 through which the elements 56 may be passed and screwed into engagement with the tubing 26. The upper end of the channel 55 forms an abutment which serves in cooperation with the element 56 to limit downward movement of the booster relation to the piston tube 26.

The above recited pump structure is designed to have the piston body 34 and the contiguous surface of the barrel A in the zone of travel of the piston body continuously submerged in and between bodies D—D' of lubricating oil, the body D extending above the piston body and completely filling the space surrounding the upstanding sleeve 36 on the piston body and partly filling the space surrounding the upper portion of the depending inner sleeve 21 and extending downward into the interior of the sleeve 36 a portion of the length thereof. The oil body D' lies below the piston body and extends downwardly below the lower end of the latter to the upper end of the booster C, and also fills the passages 38 in the piston body. The oil bodies D—D' meet in overlying relation to the piston body and completely encompass the working face of the latter by reason of leakage past the sealing rings 35 of the piston.

A third body D'' of lubricating oil occupies the upper major portion of the space exteriorly of the booster C, and below the piston head 44, and provides a sealing film of lubricating oil on the inner face of the pump barrel; this oil body D'' meeting a body of mercury occupying the lower portion of such space as will presently be described.

An important feature of the invention resides in collectively confining the oil bodies D—D'—D'' between bodies E—F as shown in Figs. 8, 9 and 10, the mercury body E occupying the inner lower portion of the pump barrel A and extending upwardly from the lower end of the latter to a point submerging the lower portion of the booster C both interiorly and exteriorly thereof and submerging the lower end of the piston tubing 26 and meeting the lower end of the oil body D'' and the mercury body F being disposed in the pump barrel A above the fixed depending sleeve 21 carried by the latter which body fills the sleeve 21 and the lower part of the sleeve 36, with a portion of the mercury body F extending into the space between the sleeves 21 and 36 and meeting the oil body D therein, this portion of the mercury body and the telescoped sleeves 21—36 forming a trap.

A column G of the mercury body E constituting an extension of the latter extends upwardly around the stand pipe 18 within the piston tubing 26 and terminates at a point below the valve 19 on the upper end of the stand pipe, the upper end of the column G and the surface of the mercury body F extending on substantially

adjacent planes which lie well below the piston valve 31 when the piston is in its lowermost position. The relative levels of mercury column G and the mercury body F vary as the piston moves on its up-stroke, the mercury body F moving up with the piston, while the column G moves down.

The surfaces of the pump parts contacted by the mercury, including all tubes and extensions are coated with a material, such as silver or the like, with which the mercury will amalgamate to provide an amalgam coating to prevent fluids being pumped from adhering to the plated surfaces and also to afford a cleansing action during the pumping operation. The several coated surfaces are shown in section by heavy lines in Figs. 8, 9 and 10 and are indicated by the reference character y. In some instances the coated surface may be formed by applying the amalgamating material directly to the surface by a plating operation, while in some cases the pump surface involved may be covered by a thin flexible sheet of metal, such as copper, having a plated outer surface.

In assembling the pump a suitable quantity of mercury is first poured into the pump barrel A to partly form the body E around the base of the stand pipe 18, whereupon a measured quantity of lubricating oil is poured into the pump barrel and imposed on the previously applied mercury to later form the oil body D'.

The pump piston B free of the coupling 27 and with the booster assembled in its lowermost position on the lower end thereof, is inserted in the upper end of the pump barrel and lowered therein until the lower end of the piston body 34 is spaced slightly above the upper end of the pump barrel. A measured quantity of lubricating oil is then poured into the pump barrel beneath the piston body 34 to form the oil body D' between the lower end of the piston body and the upper end of the booster C. The piston is again lowered to a point where the upper end of the sleeve 36 is adjacent the upper end of the barrel whereupon a measured quantity of mercury is poured into the sleeve 36 to form the lower portion of the mercury body F. The sleeve 21 is then positioned around the tube 26 and held suspended with the latter with the ring 22 positioned slightly above the opening 23. A quantity of lubricating oil is then introduced through the opening 23' to fill the space 25 beneath the ring 22 above the piston body and above the previously applied mercury, within the sleeve 36. The ring 22 is then fixed in place on the pump barrel by means of the screws 23 whereby seating the openings 23'.

The mercury body F is then built up to the desired level above the ring 22 and is preferably capped by a floating expansible sand buffer ring 60. The ring 60 is formed of rubber or the like and slightly spaced from the inner periphery of the barrel A and from the outer periphery of the piston tubing 26, and forms a bridge for supporting thereabove such sand and grit as may be deposited thereon settling from static liquid in the pump barrel to prevent or at least minimize fouling or contamination of the mercury body F by such substances; the ring 60 being designed to expand laterally under pressure of the head of liquid being pumped so as to have wiping contact with the pump barrel A and the upper extension 26 of the pump piston so that sand and grit may settle thereon as when the pump is idle, and thus be prevented from working down into the mercury and the piston sealing oil.

The piston is then shoved down to its lowermost position together with the booster C, which displaces the previously applied oil then encompassing the booster which moves upwardly into the space between the booster wall 42 and the pump barrel to form the oil body D''. Air entrapped between the oil body D'' and the piston head 44 is exhausted through a vent A' formed in the pump barrel at a point just beneath the piston head 44 when in its lowermost position, and which vent is then sealed

by a plug A². A quantity of mercury is then poured into the upper end of the piston tubing 26 from which the coupling 27 is detached, to substantially fill the latter, mercury thus applied forming the column G in continuation of the mercury body E.

The coupling 27 is then applied to the upper end of the tubing 26 after which a section of pump rod 29 is attached thereto and sections thereof and of the pump barrel A are assembled to complete the pump structure which is lowered into a well casing all in the usual manner:

As a means for collecting fine metallic particles such as are abraded from the inner surface of the pump barrel and for preventing such particles from being circulated in the oil body D and thereby be caused to abrade the working faces of the pump barrel A and piston body 34 the latter is equipped with magnetic traps comprising circumferential channels 61 formed at suitable points in the piston body, in which channels are mounted permanent magnets 62 adapted to attract metallic particles brought opposite the channels and cause them to be collected and retained in the channels for subsequent removal.

As a further means for collecting such particles a trap therefor is provided on the upper end of the booster C as shown in Fig. 10 which comprises an annular basin 63 formed of resilient material having a permanent magnet 64 arranged in the bottom thereof for attracting and collecting metallic particles settling over the booster C.

In the operation of the pump shown in Figs. 1 to 10 inclusive upward movement of the piston B with consequent lowering of mercury column G effects intake of the liquid from the stand pipe (previously filled) past the check valve 19 and into the piston tubing 26. On downstroke of the piston B (check valve 19 then being closed) entraps the liquid in the tubing 26 above the mercury column G so that as the piston moves downwardly and mercury column G moves up such entrapped liquid will then flow past the valve 31 and out of the cage 30 into the pump barrel above the mercury body F. During this downstroke operation the mercury column G rises within the tubing 26 to its uppermost position when the stroke is completed. Continued reciprocation of the pump piston effects delivery of the liquid through the pump barrel and its ultimate discharge therefrom on the upstroke of the pump piston in the manner common in reciprocal pump operations.

On upward movement of the piston the column of lubricating oil D thereabove will in most part be caused to move therewith causing displacement of the oil in the upper portion of the space 25 so that a portion thereof will move downwardly into the space within the upper portion of the sleeve 36 thus displacing the body of mercury interposed between the sleeves 21 and 36 and thereby elevating the mercury column F and the column of liquid being pumped imposed thereon slightly more than the distance of travel of the piston.

During the upstroke of the piston B the lubricating oil encompassing the piston body 34 and possibly a portion of the oil body D entrapped above the piston body will leak past the piston seals 35 and be added to the body of oil D' at the lower end of the piston body due to the high pressure of the head of the liquid being pumped, thus increasing the volume of oil between the piston body 34 and the upper end of the booster C, and thereby moving the latter downward such distance as to accommodate the added oil, the booster moving downward while the piston moves upward against the resistance of the resilient rings 45 and springs 57. However, on upward movement of the pump piston body 34 the body of liquid therebeneath will move bodily upward therewith; the upwardly moving oil D' being followed by the mercury body E supplemented by mercury from the column G which moves downward and will then pass to the lower end of the tubing 26 and through the lower end of the booster C, the valve 49 opening under the urge of

the down flow of mercury from the interior the tube 26 and of the booster shell 42, into the lower end of the pump barrel. However the parts at the lower end of the booster are of such loose fit on extension 26 as to permit the escape of a portion of the mercury from the lower end of the booster without opening the valve 49.

Downward movement of the booster C relative to the pump piston occurs during the upstroke of the piston B only under the influence of leakage of oil past the piston body of the booster C being designed to accommodate requisite longitudinal movement thereof under a maximum amount of leakage of oil past the piston body as will be likely to occur. Downward movement of the booster C may be limited by the upper ends of the channels 55 on the booster shell 42 abutting the projections 56 on the piston tubing 26.

At the peak of the piston upstroke and as the piston starts down pressures on the inner and outer columns of mercury are equal, and at this time the valve 48 on the booster C, if opened on the piston upstroke, will close under the urge of the spring 52.

As the pump piston B moves downward pressure is built up on the mercury body E beneath the piston body 34 by reason of valve 48 being closed and leakage past the valve 48 and standpipe being insufficient to take care of the mercury displaced by downward movement of the piston. Such pressure will act to force the booster C upwardly relative to the then downwardly moving piston, thereby forcing a portion of the oil body D' beneath the piston body upwardly through the passages 38 past the valve 39 which latter opens under pressure of the oil therebeneath, thus adding such oil to the body D above the piston body 34 from whence it came.

The booster C is designed to function to effect delivery of a quantity of the oil from beneath the piston body to above the piston body equal that previously leaked past the sealing rings on the upstroke of the piston. Since the amount of such leakage is variable the action of the booster C must vary accordingly for which purpose its range of longitudinal movement is variable relative to the length of stroke and movement of the pump piston. This variable movement of the booster C is rendered possible by its frictional engagement with the piston for longitudinal movement relative thereto afforded by the rings 45.

Upward movement of the booster C, relative to the downwardly moving piston B, due to pressure of trapped mercury body E, is limited by the lower end of the piston tubing 26 engaging the flange 43 with consequent opening of the valve 48 and relieving the mercury pressure on the booster C.

This opening of the valve 48 places the mercury body E and mercury column G in free communication with each other so as to permit continued downward movement of the pump piston without further upward movement of booster C relative to tubing 26.

The booster C will thus be disposed in its uppermost position on the piston tubing 26 when the piston B is in its lowermost position but on initial upward movement of the piston when the load of the liquid being pumped is directed through the mercury body F to the oil body D above the piston body through the trap afforded by the sleeves 21-36, then a portion of the oil body D may start leaking past the piston to force the booster downward proportionately to oil leakage, thus commencing another cycle of operation of the booster as above described.

It is to be noted that the annular basin 63 on the upper end of the booster C will act in co-operation with the rings 45-46 to prevent or at least minimize the leakage of oil past the piston head 44 of the booster, which leakage however is further rendered negligible by reason of the ease of movability of the booster under the pressures of the leakage oil imposed thereon.

In the modified form of the invention depicted in Figs. 11 to 16 inclusive, the same general combination of elements is employed as in the form shown in Figs. 1 to 10 inclusive except that in the modification an internal piston is employed which works on the standpipe instead of on the pump barrel.

In Figures 11 to 16 inclusive, H indicates the pump barrel, and I indicates generally the body of the pump piston which in this instance encircles the stand pipe J and has an inner working face cooperating with the outer face of the latter.

The pump barrel H is fitted at its lower end with an intake section c screwed thereon and has its upper end leading to a point of discharge. The section c is equipped with a foot valve d in an enclosing housing e from which leads the stand pipe J extending axially of and spaced from the barrel H and fitted at its upper end with a ball check valve f in a cage g. The upper end of the housing e is formed with a taper e'. Mounted on the stand pipe J is a fixed sleeve h which encompasses the stand pipe J in spaced relation thereto and is spaced inwardly from the pump barrel H. The sleeve h is open at its lower end and is closed at its upper end by a wall i.

The piston body I is formed on its upper outer margin with an upwardly extending cylindrical portion K which extends above the upper end of the stand pipe J and connects with a cage L attached to the lower end of the pump rod M. The cage L houses a foot valve N normally closing a passage O in a cap P on the upper end of the cylinder K which passage opens to the interior of the latter, the cap P constitutes the upper end of the pump piston.

Mounted on the piston I interiorly of the cylinder K is an upstanding sleeve j which extends upwardly interiorly of the downwardly extending sleeve h in spaced relation thereto; the sleeve j encircling the stand pipe J and spaced therefrom. The lower end of the piston body I is formed with a reduced tubular extension k which encircles the stand pipe J in spaced relation thereto.

Mounted on the inner face of the piston body I is a series of piston seals l-l' suitably spaced apart which seals slidably abut the stand pipe J. Formed in the piston body I is a series of elongated vertically extending chambers m which open to the upper end of the piston body through passages n and are closed at their lower ends by an annulus p detachably secured to the lower end of the piston I by bolts q. Leading from the lower end of each of the chambers m is a passage r formed in the annulus p which passage leads to the lower end of a passage s extending upwardly in the piston body I and opening to the interior of the latter adjacent to the upper end thereof through a port t located between adjacent piston seals l-l'.

The lower end of the passage s connects with a passage u leading to the lower end of the piston interiorly of the tube k which passage u is fitted with a downwardly opening check valve v.

Mounted in each of the chambers m is a plunger w between which and the upper end of the chamber m is interposed an expansion spring x tensioned to yieldably oppose upward movement of the plunger w and to effect downward movement of the latter.

The lower portions of the chambers m beneath the plungers w are filled with a body R of lubricating oil, as are the passages r, s and u. A column S of the lubricating oil fills the upstanding tube j and the upper portion of the depending tube h which column leads downwardly along the interior of the piston body I and connects (by leadage past the sealing rings l-l') with a column T of the lubricating oil leading downwardly a portion of the length of the tube k. The lower end of the oil column T in the tube k meets a mercury body U which extends into the interior of the lower end portion of the tube k and occupies jointly with the oil body T the space within the

pump barrel H beneath the piston body I and also extends upwardly in a column U' around the piston body I and around the cylindrical extension K thereof to a point near but below the upper end thereof when the piston is in its lowermost position.

The interior of the cylindrical extension K is filled with a body of mercury V which extends upwardly into the sleeve h and meets the lubricating oil therein; and which body of mercury V occupies the space interiorly of the cylinder K to a point below but adjacent to the valved upper end of the stand pipe J. The body of mercury above the piston body I extends through the passage n into the space in the upper portion of the chamber m above the plunger w.

The surfaces of the pump structure contacted by the mercury are plated with a material, such as silver or the like, as indicated at y' with which mercury will amalgamate to provide an amalgam coating to prevent fluids being pumped from adhering to the plated surfaces and to also afford a cleansing action during the pumping operation.

In assembling the pump shown in Fig. 11, the piston I with the caps P and p removed is assembled on the stand pipe J apart from the pump barrel H by inserting the pipe J downwardly through the piston I, the sleeve h and the valve assembly f—g being previously attached to the pipe J. The resultant assemblage is then placed in the pump barrel H with the end intake section c removed whereupon the barrel with the piston therein is inverted and lubricating oil is poured into the then open ends of the chambers m and passages s to fill them whereupon the cap p is applied to the lower end of the piston. A measured quantity of oil is then poured into the tube k after which the intake section c with the valve d and housing e thereon is screwed onto the stand pipe J upon which the piston I is then positioned so that the tapered end e' of the housing e abuts and closes the end of the tube k to confine the oil body therein.

The intake section C is then screwed on the adjacent end of the pump barrel whereupon the assemblage is righted and a quantity of mercury poured into the barrel to form the body U thereof. A measured quantity of mercury is then poured in the cylinder K to form a portion of the body V thereof, until it stands at a desired level in the trap formed by the sleeve h—j. A plug z' in the wall i is then removed and the chamber below said wall and above the mercury body V in the trap is then filled with lubricating oil to form the body S after which the plug Z' is replaced. Mercury is then added to the cylinder K to the required depth. A slight lift on the piston assembly unseats the tube k from the foot valve housing e whereupon the mercury body U will entrap the oil body T confined in the tube k. The cap P is then applied to the piston cylinder K and connected to the pump rod M for operation.

In the operation of the pump shown in Figs. 11 to 16 inclusive the pumping action of the piston is opposite that of the pump shown in Figs. 1 to 10 inclusive, in that the lift and discharge of the liquid being pumped is effected on the downstroke of the piston rather than on the upstroke thereof. In this instance, upstroke of the piston body I induces the liquid being pumped from the valved upper end of the stand pipe J into the upper end portion of the piston cylinder K about the mercury body V therein. On downstroke of the piston body I the mercury body U is displaced into the column U' thereby elevating the latter together with the pumped liquid imposed thereon and thus advancing the latter upwardly to discharge.

During the up and down strokes of the pump piston the entrapped oil body S above the piston body I will surge back and forth in the trap formed by the telescoped sleeve j and h, while the oil body T beneath the piston body will be carried up and down in the piston extension k. In this instance the built-in chambers m and plungers w with their associated parts constitute boosting means

whereby the oil bodies S and T will be maintained at uniform volumes or at least substantially so. This is accomplished in the following manner:

On upstroke of the piston wherein the valve N is maintained closed, a negative pressure is induced within the piston which is imparted to the mercury body V and oil column S thus establishing negative pressure above the plungers w in the chambers M. Downward pressure of the liquid being pumped imposed on the mercury column U' and mercury body U is transmitted to the oil body T thereby forcing a portion of the latter upwardly past the group of sealing rings l below the port t. Due to the resistance of sealing rings l' above the port t and to negative pressure above the plungers m the oil leaking past the rings l will be induced to pass through the ports t and passages s—u into the chambers m below the plungers w.

On downstroke of the piston when the valve N opens pressures are equal above and below the piston, so that the plungers w in the chambers m will then be advanced under the urge of the spring k (previously tensioned by upward movement of the plungers under pressure of leakage past the sealing rings l) thereby forcing oil from the chambers m through the check valve v back into the oil body T and thus restoring the equivalent of the oil previously forced past the sealing rings.

Generally considered, it will be seen that in each of the above described applications of the invention the working face of the pump piston is maintained submerged in a body of lubricating oil which extends above, below and around the working face of the piston and is confined between separated bodies of mercury protected and held in place within the pump barrel in chambers plated with a material capable of amalgamating with mercury and in such fashion that the piston will work at all times with its working face lubricated by the lubricating oil and maintained out of contact with the mercury, and that the recited arrangement of traps and seals all abrasives and solids contained in the liquid being pumped, as well as the mercury, will be prevented from contacting or entering between the contiguous working surface of the barrel and piston.

I claim:

1. In an oil well pump, a pump barrel, a piston operatively contained in said barrel comprising a piston body having a reduced diameter portion extending below said body and a reduced diameter portion extending above said body, said extensions being spaced from said barrel, bodies of lubricating oil confined in said barrel surrounding said piston and a part of said reduced diameter portions, and fluid means preventing the escape of the lubricating oil from said barrel and also preventing the mixing with said oil of liquid being pumped, and means carried by the lower of said reduced diameter portions for boosting lubricating oil from beneath to above said piston body to compensate for leakage downward past the piston body.

2. In an oil well pump, a pump barrel, a piston operatively contained in said barrel comprising a tubular, piston body having an externally reduced diameter tubular end portion extending below said body and an externally reduced diameter tubular end portion extending above said body, said extensions being spaced from said barrel, bodies of lubricating oil confined in said barrel surrounding said piston and portions of said reduced diameter extensions, and fluid means preventing the escape of the lubricating oil from said barrel and preventing the mixing with said oil of liquid being pumped, said fluid means consisting of two bodies of mercury one of which is entrapped interiorly of said piston and partially externally of the lower end portion of the lower piston extension, and the other of which is entrapped on the outside of the upper extension of said piston; the surface of the pump contacted by the mercury consisting of a material with which mercury will amalgamate.

3. In an oil well pump, a pump barrel, a hollow piston

operatively contained in said barrel comprising a piston body having a reduced diameter portion extending below said body and a reduced diameter portion extending above said body, said extensions being spaced from said barrel, bodies of lubricating oil confined in said barrel surrounding said piston and portions of said reduced diameter extensions, and means preventing the escape of the lubricating oil from said barrel and preventing the mixing with said oil with the liquid being pumped; said means consisting of two bodies of mercury one of which is entrapped interiorly of said piston and partially externally of the lower end portion of the lower piston extension, and the other of which is entrapped on the outside of the upper extension of said piston, there being a trap in said barrel above said piston body comprising a pair of telescoping outer and inner sleeves, the outer sleeve of which is closed and affixed at its lower end to the upper end of said piston body and extending upwardly therefrom while the interior sleeve is fixed at its upper end to the pump barrel and extends downwardly in laterally spaced relation to the outer sleeve on the piston body; the upper end of said inner sleeve being open interiorly to said pump barrel and being sealed exteriorly thereof to said pump barrel the lower portion of the space between said sleeves being filled with mercury and the upper portions of the space between said sleeves being filled with lubricating oil, the surfaces of the pump contacted by the mercury consisting of a metal with which the mercury will amalgamate.

4. In a pump embodying a barrel, having a valved inlet at its lower end, a stand pipe in the barrel leading from the valved inlet and fitted at its upper end with a check valve, and a tubular piston in said barrel encompassing said stand pipe having a valved upper end above the stand pipe connected to a pump rod; said piston having a body portion fitted with external sealing rings slidably engaging said barrel and being submerged in a body of lubricating oil, and mercury bodies confining said lubricating oil and separating it from the liquid being pumped; the surfaces contacted by the mercury consisting of silver.

5. The structure called for in claim 4 in which lubricating oil above the piston body is subject to leaking past the piston sealing rings under pressure of the head of liquid being pumped, together with booster means carried by said piston and controlled by movement thereof operable to return the equivalent of the leaked oil back to the oil above the piston.

6. In a pump embodying an upstanding barrel having an inlet at its lower end, a stand pipe in the barrel leading from the inlet, a foot valve in the lower end of said stand pipe normally closing the barrel inlet, a check valve at the upper end of said stand pipe, and a hollow piston in said barrel into which said stand pipe extends; said piston including a body portion carrying sealing rings and having tubular extensions of reduced external diameter on its upper and lower ends, the extension on the lower end of the piston being open and the extension on the upper end of the piston extending above the upper end of the stand pipe being fitted with a traveling valve and connected to a pump rod; an inner sleeve in said barrel fixed at its upper end relative thereto above said piston body, said sleeve being externally closed at its upper end to said barrel and open at its lower end, a sleeve carried by said piston telescoped relative to said first named sleeve and spaced therefrom; said outer sleeve being closed at its lower end and opening at its upper end to said pump barrel, a body of mercury entrapped in the lower end portion of said pump barrel extending upwardly around the lower portion of the tubular extension on the lower end of said piston body and extending interiorly of said piston around a major portion of the length of said stand pipe, a second body of mercury above and carried by said piston body extending upwardly around the lower portion of

said upper piston extension and between said telescoped sleeves, and a body of lubricating oil interposed between said bodies of mercury extending into the lower of said tubular extensions and overlying the outside of the piston body and extending above said piston around said telescoping sleeves and meeting the mercury between said sleeves; the surfaces of the pump contacted by the mercury being formed of a material with which the mercury will amalgamate.

10 7. The structure called for in claim 6 together with means carried on and controlled by the lower extension of said piston body for boosting oil from beneath to above said piston body to compensate for leakage of said oil downward past the sealing rings.

15 8. In a pump embodying an upstanding pump barrel having an inlet at its lower end, a stand pipe in said barrel leading from said inlet, a foot valve in the lower end of said stand pipe and a check valve at the upper end thereof, and a hollow piston body in said barrel into which said stand pipe extends; said piston body including a cylindrical body portion having sealing rings on its outer periphery and having axial tubular extensions of reduced internal diameter on its upper and lower ends encompassing said stand pipe, the extension on the lower end of the piston being open and the extension on the upper end of the piston extending above the upper end of said stand pipe, said upper extension being fitted with a traveling valve, and connected to a pump rod and being open to the pump barrel above said traveling valve; said piston body being formed with longitudinal passages leading therethrough, a spring pressed valve carried by said piston normally closing said passages, a body of lubricating oil in said barrel overlying the upper end and side of said piston body, and a second body of lubricating oil underlying said piston body, a mercury body in said pump barrel underlying the oil body beneath the piston body, a mercury column in said tubular extensions imposing pressure on said second body of oil, and a booster element in said barrel carried by said lower piston extension and spaced beneath said piston body operable by the pump head pressure on said mercury to force lubricating oil from beneath said piston body through said passages to the body of oil above said piston body; the surfaces of said pump contacted by the mercury being formed of a material with which mercury will amalgamate.

45 9. In a pump embodying an upstanding pump barrel fitted at its lower end with an intake section formed with an inlet, a stand pipe leading from said inlet equipped with a foot valve at its lower end; a tubular piston in said barrel encircling said stand pipe having an enlarged cylindrical tubular piston body carrying sealing rings on its outer periphery and having tubular extensions on its upper and lower ends encompassing said stand pipe, and a valved connection between said upper extension of said piston and a pump rod; said piston body having a valved passage extending longitudinally therethrough, a mercury body in said barrel submerging the lower end portion of the extension on the lower end of said piston, said column of mercury extending between said piston and said stand pipe to near but below the upper end of the latter; a body of lubricating oil in said barrel beneath said piston body encompassing a portion of said lower extension above a lower portion of said mercury body, a second body of lubricating oil entrapped above and surrounding said piston body, a second mercury body in said barrel sealing said entrapped second body of lubricating oil from liquid being pumped and acting under hydraulic pressure to impose a load thereon tending to force oil from said second body past said piston to the underside thereof, and a booster means in said barrel carried by said lower extension beneath said piston body for boosting lubricating oil from beneath said piston body through the passage in said piston body into the oil body above said piston, said means embodying a tubular shell encompassing the lower extension of said piston having a piston head submerged

in the oil body beneath the piston body and having a valved lower end submerged in the mercury body beneath said oil body, said piston head having outer sealing rings engaging said pump barrel and inner sealing rings engaging said lower extension, said piston head and shell being moveable relative to said piston body under urge of pressure imposed on the mercury body therebeneath to elevate said piston head, and means frictionally carried by said lower extension whereby downward movement of said piston will move said piston head and shell to discharge leaked oil downwardly; the surfaces of the pump contacted by the mercury being formed of a metal with which the mercury will amalgamate.

10. In a pump, a pump barrel, a reciprocal piston therein having a tubular piston body formed with a longitudinal passage therethrough an upwardly opening valve on said piston body normally closing said passage, a reduced diameter tubular extension on the lower end of said piston body, a body of mercury entrapped in the lower end of said pump barrel, a column of mercury in said piston and extension meeting said body of mercury, a booster element in said barrel encompassing and carried by said extension having a piston head sealed against said barrel and against said extension, a body of lubricating oil beneath said piston head extending between said piston head and said body of mercury, and a body of lubricating oil extending above the upper end of said piston body and surrounding the latter and subject to leaking past said piston body into the oil body beneath said piston body and then displace said booster element downwardly; said booster element being moveable upwardly under fluid pressure imposed thereon by said mercury column to force oil from said last named oil body through said passage to above said piston body; the parts of the pump contacted by said bodies of mercury and said column of mercury being surfaced with a material with which mercury will amalgamate.

11. In a pump, a barrel having upper and lower portions of its interior surfaced with silver, an upstanding silver coated stand pipe in said barrel having a valved end, a tubular piston body telescoping said stand pipe and slidably contacting said barrel, reduced tubular extensions on the upper and lower ends of said piston body having their inner and outer surfaces silver coated, a coupling on the upper end of the upper extension for connection with a pump rod, a valve in said coupling normally closing said upper extension, a body of lubricating oil in said barrel overlying each end of said piston body and surrounding the inner end portions of said extensions, mercury bodies confining said bodies of oil and preventing contamination thereof by fluid being pumped, and means carried by said lower extension for creating an upward pressure on the body of oil beneath the piston body on downward stroke of the latter to force a portion thereof past the piston into the oil body above the piston body.

12. In a pump, a barrel having its lower and its upper interior surfaces plated with silver, an upstanding silver plated valved intake tube in said barrel, a silver plated tubular piston having a body in slidable sealing operative contact with said barrel telescoping said intake tube in spaced relation thereto and having silver plated reduced end extensions above and below said body, a valve attached to and closing the end of said silver plated extension above said tube and providing a connection for a sucker rod, said reduced piston extensions spaced from said barrel to provide chambers above and below said piston body, a valve controlled passageway connecting said chambers for returning to the upper chamber leakage that may occur from the upper chamber to the lower chamber, a body of lubricating oil in each of said chambers, a booster piston in said lower chamber within the lower body of lubricating oil and mounted on the lower piston extension and arranged to position itself according to the quantity of oil in said chamber and connected to a control valve controlled by the downward movement

of said booster, a pair of spaced outer and inner telescoping silver plated tubes above said piston the inner of which is sealingly connected to said barrel in the upper chamber and having upper and lower ends and the outer of which is attached to said piston and having a closed lower end and an open upper end, said tubes being arranged to telescope each other to varying degrees according to the position in said barrel of said piston, the oil in the upper chamber extending into the spaces between said telescoping tubes, a body of mercury in said silver plated pump barrel above said piston body between the barrel and the reduced upward extension of the piston and encompassing the telescoping tubings and meeting the lubricating oil in said tubing interiorly of one of said tubes to effect a yieldable seal for the upper oil chamber and serve as a protector against pumped fluid from entering said lubricating oil, a body of mercury interiorly of said silver plated piston extending down and around the silver plated upstanding tube and filling the space below said piston body and entrapping the lubricating oil above and below said booster piston, a valve controlled by the movement of mercury urging said booster piston to move upwardly returning any oil leakage through said valve controlled passage when pumping action moves said tubular piston downwardly, said mercury in co-operation with the silver lined piston tubes and extensions affording a trap for the lubricating oil and a seal preventing the pumped oil from inter-mixing with the lubricating oil.

13. In an oil well pump a partially silver plated pump barrel, an upstanding silver plated intake tube fitted with a pair of normally closed upwardly opening valves, a hollow silver plated piston in said pump barrel telescoping said tube and spaced therefrom to provide a fluid working chamber, said piston having a reduced lower extension and also a reduced upper extension provided with a normally closed upwardly opening valve, each of said extensions being silver plated interiorly and exteriorly, said extensions being spaced from said pump barrel forming an upper chamber and a lower chamber each of which is provided with a quantity of lubricating sealing oil for lubricating the working contacting surfaces of the piston and barrel, a silver plated outer sleeve sealingly attached to the piston and extending open end up, a silver plated sleeve open at its end and sealingly attached to the barrel, said last named sleeve telescoping said first named sleeve in spaced relation thereto, the oil in said upper oil chamber extending up into the telescoping silver plated sleeves, a body of mercury between the upper piston extension and the pump barrel trapping said upper body of lubricating oil in the telescoping sleeves permitting rise and fall of the oil in the spaces provided yet preventing loss of said oil or intermixing with pumped fluid, a body of mercury interiorly of said hollow piston and extending downward and beneath the piston body to the wall of the silver plated barrel protecting said lower body of lubricating oil against loss by leakage and preventing pumped oil from contacting said lubricating oil, and a booster carried by said lower piston extension for returning quantities of lubricating oil from one chamber to another during a pump stroke operation, there being a valve controlled passage in said piston connecting said chambers.

14. In an oil well pump embodying a pump barrel, a reciprocating piston in said barrel having a reduced upper end portion, and a body of mercury in said barrel interposed between said piston and liquid being pumped and surrounding said end portion and an expandable buffer ring floated on said mercury body.

15. In an oil well pump, a pump barrel, an upstanding valved intake tube in said barrel, a hollow piston telescoping said standing tube and spaced therefrom providing a fluid flow passageway, said hollow piston having a body in operative contact with said barrel, a body of sealing lubricating oil in said pump barrel above said piston body, a body of sealing lubricating oil in said pump barrel im-

mediately below said piston body, a body of mercury confined in said pump barrel immediately below the lower oil body a body of mercury above said piston body, and trap means carried by said barrel and piston and arranged above said piston for preventing the mercury above the piston from contacting the barrel and preventing the lubricating oil above the piston from contacting the oil being pumped.

16. In an oil well pump, a pump barrel, an upstanding valved intake tube in said barrel, a hollow piston telescoping said standing tube and spaced therefrom providing a fluid flow passageway, said hollow piston having a body in operative, contact with said barrel, a body of sealing lubricating oil in said pump barrel above said piston body, a body of sealing lubricating oil in said pump barrel immediately below said piston body, a body of mercury confined in said pump barrel immediately below the lower oil body a body of mercury above said piston body, trap means carried by said barrel and piston and arranged above said piston for preventing the mercury above the piston from contacting the barrel and preventing the lubricating oil above the piston from contacting the oil being pumped, and a flexible buffer ring on the upper surface of upper body of mercury.

17. In an oil well pump, a pump barrel, an upstanding valved intake tube in said barrel, a hollow piston telescoping said standing tube and spaced therefrom providing a fluid flow passageway, said hollow piston having a body in operative, contact with said barrel, a body of sealing lubricating oil in said pump barrel above said piston body, a body of sealing lubricating oil in said pump barrel immediately below said piston body, a body of mercury confined in said pump barrel immediately below the lower oil body a body of mercury above said piston body, and trap means carried by said barrel and piston and arranged above said piston for preventing the mercury above the piston from contacting the barrel and preventing the lubricating oil above the piston from contacting the oil being pumped, all pump surfaces contacted by mercury formed of a material with which mercury will amalgamate.

18. In a pump embodying an upstanding pump barrel fitted at its lower end with an intake section formed with an inlet, a stand pipe leading from said inlet equipped with a foot valve at its lower end and a check valve at its upper end; a tubular piston in said barrel encircling said stand pipe having an enlarged cylindrical tubular piston body carrying sealing rings on its inner periphery contiguous said standpipe, a tubular extension on the lower end of said piston body encompassing said stand pipe and spaced therefrom; a body of mercury confined in said pump barrel submerging said piston body and said extension, a body of lubricating oil interiorly of said extension meeting said mercury body extending interiorly of

said piston, a body of lubricating oil entrapped above said piston and meeting said first named body of oil; said first named body of oil being subject to being forced upwardly past said piston body interiorly thereof under pressure imposed on said mercury body, and booster means carried by said lower end extension of said piston body for forcing return of said oil to its original position; the surfaces in said pump contacted by the mercury being covered with a material with which mercury will amalgamate.

19. The structure called for in claim 18 wherein said last named means comprises a chamber in said piston body, a passage leading from the lower end of said chamber to the inner upper portion of said piston, a plunger in said chamber, a body of lubricating oil in said chamber beneath said plunger and filling said passage, and springs bearing between said piston and plunger for depressing said plunger to force oil from said chamber through said passage to the interior of said piston.

20. In an oil well pump embodying an upstanding pump barrel, a tubular piston operatively contained in said barrel, a lower end wall on said pump barrel having an inlet passage fitted with a foot valve, a stand pipe leading upwardly from said inlet through said piston to a point thereabove having its upper end fitted with a check valve, a pair of spaced tubular sleeves telescopically arranged in said barrel above said piston including an outer sleeve and an inner sleeve, said outer sleeve having an open upper end and being closed at its lower end and affixed to said piston, said inner sleeve being open at its ends and having its upper end fixedly connected to said pump barrel in sealed engagement therewith; a lubricating oil body surrounding said piston and extending immediately above and below said piston with the oil body above said piston surrounding and extending above said outer sleeve and filling the upper portion of the latter, a body of mercury in said outer sleeve beneath the oil therein filling said inner sleeve and extending into the space in said pump barrel immediately above the upper end of said sleeve and a second body of mercury trapped in the lower end portion of said pump barrel immediately below the body of lubricating oil and extending upwardly into said hollow piston around said stand pipe.
